DISPLAY CARD FOR A JUMPING BEAN GAME

Clifford M. Irvin, Jr., 6017 Fandango, El Paso, Tex.

Filed Oct. 5, 1959, Ser. No. 57,804

Term of patent 3½ years

(Cl. D80—9)

Fig. 1

Fig. 3

Fig. 1 is a front perspective view of a display card for a jumping bean game embodying my new design; and

Fig. 2 is a side elevational view thereof; and

Fig. 3 is a rear perspective view thereof on a reduced scale.

The dominant features of my design reside in full line portions of the drawing.

I claim:

The ornamental design for a display card for a jumping bean game, as shown and described.
